UNITED STATES PATENT OFFICE.

ERNEST FOGG, OF NEWCASTLE-UPON-TYNE, ENGLAND.

ARTIFICIAL TEETH.

1,070,442.

Specification of Letters Patent. Patented Aug. 19, 1913.

Application filed February 26, 1913. Serial No. 750,760.

To all whom it may concern:

Be it known that I, ERNEST FOGG, L. D. S., a subject of the King of Great Britain and Ireland, residing at 58 Jesmond road, 5 in the city of Newcastle-upon-Tyne, England, have invented new and useful Improvements in or Relating to Artificial Teeth, of which the following is a specification.

10 This invention relates to artificial teeth, and has for its object to provide improved means for improving the appearance of the same.

According to this invention I provide 15 separate filling-pieces for fitting and filling the interstices between adjacent teeth and giving the appearance of the gums.

I will fully describe my invention with reference to the accompanying drawings 20 wherein—

Figure 1 is a perspective view of a portion of a set of artificial teeth fitted with my filling-pieces. Fig. 2 is an elevation and plan to a considerably enlarged scale of 25 one of the filling-pieces illustrating one method of securing the same; Fig. 3 is an elevation and side view and Fig. 4 is a side view and plan illustrating further ways of securing the filling-pieces.

30 Referring to the drawings, according to this invention I fit between the pairs of adjacent teeth *a* (Fig. 1) filling-pieces *b*

made of porcelain, metal or any other suitable material. The filling-pieces *b* are of substantially wedge shape so that they fit 35 snugly between the teeth, and they are appropriately enameled or colored to have the appearance of the gums.

The filling-pieces are secured in any convenient manner. By way of example, the 40 filling-pieces may be provided with grooves or recesses *c* (Fig. 2) or holes *d* (Fig. 3) into which the vulcanite or material of which the plate *e* (Fig. 1), on or to which the teeth *a* are mounted or secured, is made, 45 can be pressed. Or the filling-pieces may be provided with headed or other pins or the like *f* (Fig. 4) which can be embedded in the material of the plate. In some cases the filling-pieces may be secured by any suitable cement, solder, etc. 50

What I claim and desire to secure by Letters Patent is:—

In artificial teeth, separate filling-pieces 55 for fitting and filling the interstices between adjacent teeth, and means for securing same in position.

In testimony whereof I have signed my name to this specification in the presence of two subscribing witnesses.

ERNEST FOGG.
